[57] CLAIM

The ornamental design for a dinner tray, as shown.

DESCRIPTION

FIG. 1 is a top front right perspective view of a dinner tray, showing our new design;

FIG. 2 is a top plan view thereof;

FIG. 3 is a right side elevational view, the left side being a mirror image thereof;

FIG. 4 is a bottom plan view thereof;

FIG. 5 is a front elevational view, the rear elevational view being a mirror image thereof;

FIG. 6 is a partial cross-sectional view taken along line 6—6 of FIG. 2, enlarged for convenience of illustration; and,

FIG. 7 is a partial cross-sectional view taken along line 7—7 of FIG. 2, enlarged for convenience of illustration.

FIG. 1

FIG. 2

FIG. 3

FIG. 4**FIG. 5****FIG. 6****FIG. 7**
